UNITED STATES PATENT OFFICE.

HORATIO GATES, OF WORCESTER, MASSACHUSETTS.

LABELING MACHINE.

Application filed November 21, 1921. Serial No. 516,550.

To all whom it may concern:

Be it known that I, HORATIO GATES, a citizen of the United States, residing at Worcester, in the county of Worcester and State of Massachusetts, have invented a new and useful Labeling Machine, of which the following is a specification.

This invention relates to a labeling machine of the type in which the labels are taken from a label holder intermittently by continuous rotary motion of a gumming cylinder or other gum applying device and kept in motion edgewise along a path until they come into contact with the articles to be labelled which are also moving along a converging path so that the labels can be rolled down on the surface of the article in exactly the desired position while the labels and receptacle are travelling along together.

The principal objects of the invention are to provide a label holder with means for positively holding the front of the labels whenever the label holder is not in position for applying the label to the gumming device; to provide means for operating this holder intermittently in such a way as to periodically bring the front label of a bundle in the label holder into contact with the gumming device and then remove it therefrom to allow a label to be taken off; to provide a device for holding the tops of the labels in position, which in its preferred form is operated by gravity and positively limited as to its forward motion; to provide a combination of the above mentioned devices in such a way as to eliminate the necessity of having fingers of any material length at the bottom of the label holder for preventing the labels from being accidentally dislodged from it there; to provide a follower for the labels actuated yieldingly, preferably by gravity, and guides therefor as well as a clutch device for preventing the follower moving forward and pressing on the labels in the holder when the label holder is in delivering position and to allow a yielding pressure of the labels against the drum but which will not prevent the follower from being forced back by the drum or even drawn back by hand at any time; to construct one side of the label holder in such a way that it can be turned up into a position to permit the operator to get at the labels from the side to introduce a bundle of labels or to take them out; to pro-

vide a novel means for reciprocating the label holder toward and from the gumming cylinder automatically; to provide such a label holder operating mechanism in combination with the means for driving the above mentioned gumming cylinder so that they will work together, and to provide means whereby the label holder can be disconnected conveniently so that the rest of the machine can be operated without it for trying it out; to provide an improved gumming cylinder for applying the gum to the labels and at the same time withdrawing the labels from the holder, of such a nature as to avoid the application of too much gum to the labels and to secure a continuous motion of each label from the time it leaves the label holder until it is applied to the article; to provide a simple and inexpensive means for insuring the travel of the label edgewise along with the drum throughout the path of travel and positively guide the front end of the label between the contact roll and the gumming cylinder; to provide means for regulating and distributing the gum evenly over the surface of the cylinder before applying the labels; to provide efficient means, easily detachable and replaceable, for releasing the label from the drum and altering its course so as to bring it into contact with the article to be labelled; to provide convenient means for rolling the label on the article and an effective device for preventing the article from jumping up at the rear when the pressure of the labeling roll is applied to it at the front end; to provide an improved gum box for continuously applying gum to the gumming cylinder in a uniform manner, to so arrange the gum box that whether full or nearly empty it will always deliver by gravity substantially the same amount of adhesive and do it in a uniform manner; to provide a conveyor for the articles to be labelled which can be adjusted conveniently and timed so as to bring the receptacles into positions for receiving a label just as fast as the labels are delivered; to provide improved arrangements for driving the conveyor and for adjusting its width and means for cushioning the conveyor so that the application of a label can be conducted on a yieldingly mounted support; and to provide improvements in the means for guiding the article to be labelled on the conveyor by which the article is held out of position to

reach the conveyor until the moment when it is time to receive it and then released, the same being adjustable for articles of different sizes.

The invention also involves improvements in various details of the mechanism for accomplishing the above mentioned results and for the improvement of the machine in various other particulars as will appear hereinafter.

Reference is to be had to the accompanying drawings, in which—

Fig. 1 is a side view of a machine constructed in accordance with this invention;

Fig. 2 is an elevation of part of the other side of the machine on an enlarged scale showing the label holder reciprocating mechanism;

Fig. 3 is a plan of a part of the driving mechanism on the same side of the machine;

Fig. 4 is a face view of the cam for controlling the operation of the label holder shown partly in section to illustrate the return cam;

Fig. 5 is a sectional view on an enlarged scale on the line 5—5 of Fig. 2;

Fig. 6 is a fragmentary side elevation similar to the left hand end of Fig. 1, but showing the parts in a different position;

Fig. 7 is a delivery end view of the machine, looking in the direction of the arrow 7 in Fig. 6;

Fig. 8 is a front elevation of the label holder, looking in the direction of the arrow 8 in Fig. 6;

Fig. 9 is a fragmentary side elevation showing the follower support and guide with other elements omitted;

Fig. 10 is a transverse sectional view on the line 10—10 of Fig. 8 showing the adjusting means in section;

Fig. 11 is a fragmentary side elevation of the follower guide with the clutch for stopping it shown partly in section;

Fig. 12 is a sectional view on the line 12—12 of Fig. 6;

Fig. 13 is a side elevation of the label hopper proper, showing in dotted lines the rear side wall raised and held in elevated position;

Fig. 14 is a plan of the glue pot and gumming mechanism;

Fig. 15 is a plan of the parts below the gumming cylinder with the gumming cylinder removed;

Fig. 16 is a side elevation of the frame and bearings for supporting the gumming mechanism;

Fig. 17 is an elevation of the means for driving the gum roll and gumming cylinder;

Fig. 18 is a longitudinal central sectional view on the line 18—18 of Fig. 14;

Fig. 19 is a rear elevation of the label follower;

Fig. 20 is a rear elevation of the groove cleaner for the gumming drum;

Fig. 21 is a plan of a gumming cylinder of a modified form;

Fig. 22 is a sectional view on the line 22—22 of Fig. 18;

Fig. 23 is an end view of the modified form;

Fig. 24 is a side elevation partly in section of the conveyor for the receptacles to be labelled.

Fig. 25 is a plan of the means for feeding the receptacles to the conveyor, shown on an enlarged scale and in position for holding a receptacle back from the conveyor;

Fig. 26 is a side elevation of a detail looking in the direction of arrow 26 of Fig. 29;

Fig. 27 is a sectional view on the line 27—27 of Fig. 24, showing some of the parts in plan; and

Fig. 28 is a sectional view on the line 28—28 of Fig. 29 on an enlarged scale; and

Fig. 29 is a plan of the entire feeding device.

I have shown the invention in a form in which a frame 10 is employed resting on legs 11 and supporting the parts of this machine. The driving shaft 12 is driven by a belt on a pulley 13 or in any other desired manner. On this shaft are fixed two cams 14 and 15 operating two rolls 16 and 17. These two rolls are rotatably mounted on studs fixed to a yoke 18. This yoke has an elongated opening 19 therethrough for the shaft 12 to pass through. The rotation of the shaft causes the yoke to be moved in one direction by one cam and in the opposite direction by the other so it has a reciprocating motion. At one end the yoke is pivoted to the top of an upright pivoted arm 20 and at the other end it is provided with a vertical pivot 21 on which is mounted a handle 22 to swing on the axis of this pin. This handle has a passage through it and through this passage extends a horizontal connecting and pivot pin 23 having a loose head 24 located in a slot 25 in the handle 22. This pin 23 therefore moves back and forth horizontally with the handle. It passes into a bushing 26 which passes through the end of an upright pivoted arm 27 and the end of the yoke 18. The arms 20 and 27 are similar but located at opposite ends of the machine. Beyond the yoke the pin 23 when in operation, fits in a perforation in an upright pivoted arm 28 constituting one side of yoke 28. This pin therefore normally pivotally connects the yoke 18 with the arms or levers 27 and 28 but it can be withdrawn into the bushing 26 so as to disconnect the arm of the yoke 28 from the other parts. There is a yoke 29 at the other end of the machine which corresponds with the yoke 28 and is in-

105

110

115

120

125

130

tended to keep parallel with it. These yokes are pivoted at two points 30 at the ends of the machine.

The arms or levers 27 and 20 are also pivoted at the same points and they extend down below and are shown as connected across the bottom by a longitudinal bar 31 pivoted to their lower ends. It may be stated here that although the arms 20 and 29 move together they are not pivoted together or otherwise connected at the top of the arm 20 and that end of the yoke 18. In other words, there is no connection at that end corresponding with the pin 23.

The reciprocation of the yoke 18 causes the two arms 20 and 27 and the two yokes 28 and 29 to swing on their pivots uniformly and with a parallel motion.

Each yoke 28 and 29 constitutes a lever which is part of a swinging frame at the ends of the machine which is in the form of a rectangle having bottom and top cross bars. At the top a pair of longitudinal rails 32 are pivoted to the yokes 28 and 29 on horizontal axes for transmitting the rocking motion to the yoke 29 as a parallel motion. Fixed with respect to these rails 32 are side frames 33 of skeleton form which constitute means for supporting the label holder or hopper. They support a right and left hand screw 34 extending across the front. This is operated by a head 35 at one end and carries a pair of nuts 36 from which depend the two integral sides 37 of the label holder. These sides can be moved toward and from each other to adjust the width of the holder by turning this screw 34. When turned to the proper position it is held by a check nut if desired.

Carried by the yoke 28 is a cross bar 38 and carried by the side piece 37 on the right side is a pivoted hook 39. This side piece can be swung up to the dotted line position shown in Fig. 13 and the hook supported by the cross bar so that the side piece is out of the way and a bundle of labels L can be inserted, withdrawn or adjusted. They rest on a bottom plate 40 which constitutes the bottom of the label holder. The bottom plate is supported by cross pieces 41 carried by the frames 33 and has a small front lip 104.

Projecting down from each of the sides 37 is an integral arm 42 which has a cam surface 43 on the bottom adapted, when the label holder is moved forward, to engage a cross rod 44 freely rotatable on stationary studs on the yoke 28 near its point of pivotal support. This lifts the sides 37 slightly as the label holder is moved forward. This moves their lower front ends back so that they will not engage the gumming cylinder 100. This position of the parts is shown in Fig. 6.

The tops of the yokes 28 and 29 carry

guide rollers 50. I have shown these guide rollers as arranged in pairs, each roller being of grooved form to carry between them a follower beam in the form of a slide 51. This beam is of rectangular cross-section 79 and extends from one end of the machine to the other at the center. It rests on the two bottom rolls 50 and is guided by the top ones. At the front end of the machine a flexible cord or cable 52 is connected with this follower beam and extends forward over a pulley 53. It depends from that and has a weight 54 upon it which normally but yieldingly forces the follower beam forward. The rear end of the follower beam is provided with a follower frame 55 which extends down and forwardly and is provided at its lower end with a plate 56 which constitutes the rear end of the label holder. This plate is connected with the follower frame by three studs 57 mounted on the rear of the plate. Two of these studs extend into unrestricted openings in the follower frame and the other one extends into a central opening therein and is secured in 80 adjusted position by a set screw or the like. This follower is obviously pressed forward against the rear of the bundle of labels in the holder to press the labels toward the front.

On one side of the machine, as indicated in Fig. 2, there is a cam plate 60 in fixed position on the frame 10. This plate has two cam grooves or recesses 61 and 62, each of which guides a roll 63 or 64 in accordance with the motion of the label holder. These rolls are mounted on studs, one stud being fixed on a lever 65 which is duplicated on the other side and provided at the top with a cross bar constituting a label guard 66. This pair of levers and guard constitute a rigid frame pivoted near its center on two arms 67, on the end of one of which is located the roll 64. These arms are fixed rigidly together by a cross bar to constitute a frame which is pivoted by studs 67^A to the label holder frame 33. As the label frame moves back and forth with the yoke 18 the roll 64 is caused to rise in the cam slot 62 and thus swing the frame 67. When it reaches nearly the end of its stroke the roll 64 passes into a horizontal extension of the slot 62 and positively holds the guard 66 up. During the whole of this motion the roll 63 is guided in the slot 61 from the position shown in Fig. 2 to that shown in Figs. 1 and 18 and back again. This action is to swing the guard in at the front of the label holder to engage the front label and hold the label back in the holder until the label holder moves up into position for a label to be removed. Just then the action of the lever 65 swings the label guard 66 down as shown in dotted position in Fig. 18. The motion of the label holder itself, or rather 103 110 115 120 125 130

the frames 33 which carry it, is directly forward and back.

Pivots on studs 70 carried by the side frames 33 is a clutch frame 71. This has at the bottom two adjustable screws 72 adapted to engage the arms of the yoke 28 when the clutch frame moves back. This swings this frame, which is in the form of a lever, back at the top. A spring 73 engaging the screw 34 holds the frame forward at the top and yieldingly presses the heads of the screws 72 against the forward edges of the yoke 28 when it is permitted to do so. At the top, this clutch frame is provided with a clutch 74 in the form of a pivoted plate having a flat upper edge that engages the bottom edge of the follower beam. Its action is such that when the screw 72 is pressed forward the clutch will be moved back out of operative position but at other times it engages the follower beam in such a way as to permit of its being moved back by grasping the frame 55 but to prevent its being moved forward. This is brought about by pivoting the clutch 74 at a point forward of its center. In other words, the weight 54, is prevented from pressing the follower against the labels at the time at which a label is to be taken out of the label holder. At the opposite point all resistance is removed and the whole pile of labels is pulled forward by the weight. Supported by a cross-piece on the bars 32 is a fixed plate 75 for engaging the top of the follower beam opposite the clutch 74. It is adjustably mounted on two screws 76.

Pivots on a cross rod which is supported by the longitudinal rails 32 there is a depending lever 77 which has at the bottom a T-shaped guard plate 78 for engaging the top and front of the labels in the holder as indicated in Fig. 18. This hangs by gravity in the position shown therein. It has a forwardly projecting arm 79 which engages the bottom of one of the side rails so that it cannot swing forward beyond a certain limit but it can swing backwardly with the labels.

One of the features of this machine is the means for gumming the labels in the holder and withdrawing them therefrom one by one. For this purpose a gum box 80 is shown mounted on the frame 10. This gum box may be of any desired kind in general, but is intended to be sealed at the top when it is filled, and is provided at the bottom with an outlet valve casing 81 for receiving a valve 82. This valve is of a modified truncated conical shape. It is circular at each end, one of the circular ends being of larger diameter than the other, but one element of the modified cone at the bottom is horizontal while the axis is on an angle to the horizontal half as large as the angle which the opposite element makes with the horizontal.

This valve is located in the valve casing 81 which has the same external shape, and the casing is provided with a passage 83 opening from the inside of the gum box to the exterior of the casing through the bottom thereof for discharge of the gum. The valve is provided with a similar passage 84 at the bottom which, when the valve is wide open, registers with the passage 83. The valve can be turned so as to decrease the outlet for the gum as shown in Fig. 18.

The gum box has a trough 85 which receives the gum and will hold the gum at the level of the top of the effective outlet 83-84 because, no air being admitted into the top of the gum box, the gum cannot flow out of the outlet unless the level of it in the trough is depressed enough to allow air to enter over the top of the gum in the trough and through the valve.

Through the front end of the trough extends the main shaft 12 mounted in bearings on the frame, these bearings having removable caps 87 preferably. This shaft supports a gum roll 88. This gum roll is so located that the external surface will extend below the surface of the gum in the trough 85, no matter how little gum it may contain. This roll is rotated in the direction of the arrow in Fig. 18 and a scraper 89 is provided on the rear having a surface for scraping any surplus gum from the gum roll. This is mounted on a frame 90 pivoted on studs 91 and adjusted by two screws 92 screwing into the top of two arms 93 on the frame, and normally holds the scraper against the roll. The screws are mounted in lugs 94 on the frame. Nuts 95 are shown for adjusting the height of the frame 90 on which the scraper is mounted. The screws are adjusted by turning them by means of their heads and check nuts are shown for holding the adjustment.

The purpose of the gum roll is to take the gum out of the trough 85 and present it to the surface of a label gumming and carrying member 100. This cylinder is provided with circumferential grooves 101 preferably spaced equally apart longitudinally so as to provide spaced surfaces to take gum from the gum roll, and it also takes the labels out of the label holder itself. The gum roll 88 may be driven from any desired source of power but is shown as mounted on the main shaft 12 which is provided with a gear 97 meshing with a double gear 98 which drives a gear 99 on the shaft 96 of the gumming member 100.

These gears are so proportioned, preferably, as to drive the cylinders 88 and 100 at the same surface speed. The frame 10 has upwardly extending arms 93 on which the shafts 86 and 96 of these gears have their bearings. These shafts have swinging caps 102 over their ends held down by pivoted

screw eyes 103. Thus the shafts 86 and 96 can be removed readily and quickly fixed in position.

Meshing with the gear 90 is a small gear

- 105 on a cross shaft 106. This shaft has a contact or pressure roll 107 on it comprising a series of discs or circular projections 108 which together constitute an interrupted cylindrical surface having circumferential grooves between the discs alternating with the grooves in the gumming member 100, for a purpose to be described. On the other end of the shaft 106 is a gear 109 meshing with a gear 110 on a short shaft 111 supported in bearings on one side of the frame and extending through it. On the outer end of this shaft is a gear 112 meshing with a smaller gear 113 on a shaft 114 extending across the machine and provided with a guide roll made up of discs 115 spaced apart and also each one of them spaced so as to extend between an adjacent pair of discs 108. These two rolls are parallel with each other and close to each other as indicated by the fact that the discs of one project between the discs of the other.

The gear 110 also meshes with a gear 116 on a shaft 117 which carries a pressure roll 118. The three rolls 108, 115 and 118 are located half way between the two sides of the machine and they all rotate positively with the gumming cylinder 100. The pressure roll 118 is provided with a surface of soft rubber, as for example, sponge rubber, and its office is to press the label on the article B to be labelled under a light pressure and yet firmly hold it in contact therewith as soon as the label is in contact with the roll.

- 40 Mounted on one of the side frames there are three pins 120 and on the opposite side-frame there are two pins 121. These pins project inwardly toward each other and constitute supports for the opposite ends of a transverse bar 122 which carries a comb 123. The pins 120 are so located with respect to each other as to receive the L-shaped end of the cross bar 122 between them. This end rests between two of the pins and over one of them. Its rear surface projects back in contact with the center one and it just fits under the third one which is at the top. On the other end the two pins 121 are located like the first two pins 120 mentioned above. Thus the bar is provided with a stop at the rear on both ends and with a support under it. In locating it in position it is swung in at the right as shown in Fig. 18 and then the left hand end is placed in position. This fixes it and prevents its accidental dislodgment although it is readily detachable at all times. The comb 123 has teeth spaced like the grooves in the gumming cylinder and it is located so as to project into the grooves.

These teeth are concave on their forward side so that the labels on the gumming cylinder 100 will be forced from the surface thereof by the stationary comb and brought down away from it along the concave surface of the teeth of the comb 123 into contact with the receptacle to be labelled.

The grooves on the gumming cylinder 100 are cleaned by a cleaner 125 detachably mounted on legs 126 projecting inwardly from the frame. This groove cleaner is provided with projecting teeth 127 adapted to extend into the grooves and take the surplus glue out of them as the surface of the cylinder rotates past them. It is located right over the gum roll 88 so that any gum or glue dripping from it will drop upon its surface and be used over again.

I have found in practice that the application of the label to certain kinds of receptacles, as for example bottles, by such methods as this sometimes results in the elevation of the rear end of the receptacle when it first comes in contact with the pressure roll as 118. This is particularly true in travelling at high speed and in that case is apt to cause considerable difficulty. For the purpose of avoiding that, I have provided an anti-jump roll 130. This is mounted on arms 131 projecting downwardly from a cross bar 132 which extends across the machine and is pivoted on studs 133. There is an upwardly extending arm 134 from the cross bar which is normally drawn back against a fixed stop or stud 135 by a spring 136. This yieldingly presses the anti-jump roll 130 against the article to be labelled at a point which prevents its jumping up when it first comes into contact with the pressure roll 118. It will be understood from the above that this article B is intended to travel under these rolls as will be explained later.

It will be seen, therefore, that the label is fed forward by providing the constantly rotating gum cylinder for engaging the rear surface of the label while the label holder is moving toward it at high speed and immediately shifting the label holder back from contact with the cylinder. Thus, the pressure on the labels is entirely removed from the label which engages the cylinder and thus the adhesiveness of the glue on the gum roll draws the first label away from the others. In this way the uncertainty of removing a label from the label holder is practically eliminated and the danger of taking out two labels is also avoided. The shifting back of the label holder suddenly leaves the labels in a comparatively loose condition in the front of the holder but their upper ends are prevented from moving forward relatively to the label holder itself. Immediately after the label is removed from the

70

75

80

85

95

100

105

110

115

120

125

130

label holder it passes down on the surface of the gumming cylinder 100. If there is any tendency of its lower end, which very likely has not come in contact with the glue at this time, to bend outwardly away from the gumming cylinder 100 this is corrected by the guide roll with which that end will immediately come into contact. The discs on the guide roll 115 rotating at a higher surface speed, engage the front or printed side of the label and steer its forward edge upwardly into contact with the discs of the contact roll 108. These discs force the label into contact with the gumming cylinder 100 so that it will therefore pass around with that cylinder and the whole length of its rear surface will be gummed. The contact roll, like the other rolls, is rotated positively and this makes the feed of the label positive so that it can be kept in time with the feed of an article B below.

Passing from the contact roll on the surface of the gumming cylinder 100 the forward edge of the label is separated from the latter by the comb 123 and forced to travel along its concave surface as indicated in Fig. 18. The action of the gum surface 100 helps force the forward edge of the label forward into contact with the bottle or other article B. This, as will be described below, is travelling forward in the direction of the arrow while the pressure roll 118 is rotating in the same surface direction and at the same surface speed. This rolls the label on the article B as the latter passes through the machine. The teeth of the comb touch only the ungummed parts of the label.

For the purpose of feeding the bottles B or other articles to be labelled, I have provided the following mechanism. On the main driving shaft 12 gear 97 drives a train of gearing 141 that, in turn, drives a gear 142 on a shaft 143. This shaft is located at the feeding-in end of the frame 10 and is supported by a pair of bushings 144 and 145 carried by the frame and in turn constituting the pivotal supports for the yoke 29 as well as the arm 27. These bushings are supported in bearings on the frame 10 and held in position by set screws 146 so as to support these heavy parts above mentioned and also support the shaft 143 which otherwise would be required to carry the heavy weight of the frame for moving the label holder.

On the shaft 143 is located centrally a sprocket wheel 147 over which passes a sprocket conveyor chain 148 having projections 149 which are adapted to engage the rear ends of the bottles B or other receptacles to be labelled and push them along. This chain is supported at the other end by a similar sprocket wheel on an idler shaft 150. Also fixed on the shaft 143 is a driving sprocket wheel or pulley 151 operating a

sprocket chain or belt 152 which passes over a similar wheel or pulley 153 on the shaft 150 and drives it positively. The top strand of the chain 148 is arranged so it is taut and it is also arranged preferably in a nearly horizontal position. It is adjustable up and down to take care of thick and thin articles or bottles. The shaft 150 is mounted on the extreme end of a supporting frame 156 extending along beside the upper active strand of the conveyor chain 148 and constituting a platform for supporting the bottles or receptacles as they slide along propelled by the chain 148. This frame or platform is provided with a longitudinal slot through which the chain and its projections 149 project. This platform 156 is pivotally supported at the intake end of the machine by means of enlargements or hubs with which it is provided bearing on the inner ends of the bushings 144 and 145.

The platform is also supported and pressed upward yieldingly at the opposite end of the machine. For this purpose I have provided a cross bar 158 on the frame and constituting part of it. Through this passes a screw 159 arranged vertically and having a hand wheel 160 at the bottom for operating it. At the upper end this screw bears in conical concave bottom 161 of a metal plate 162. The convex side of the cone centers a spring 163, the upper end of which is centered in a recess 164 carried in the bottom of the platform 156. This platform has cross pins 165 for supporting the ends of the metal plate 162. Thus, the platform is yieldingly supported at this end, the other end being positively pivoted.

On this platform are shown side projections 167 provided with several small perforations 168. Two pairs of these projections are shown all in the plane of the platform. Into these perforations are adapted to extend pins 169 on a pair of guide bars 170. The perforations are at different distances from the chain 148 and the guide bars therefore can be set at different distances apart and are usually set at equal distances from the chain. They guide the articles to be labelled and prevent their getting out of central position.

By means of legs or projections 172 extending from a feeding-in frame 173 this frame is pivotally mounted on the bushings 144. It is provided with a pivoted longitudinally adjustable rod 174 which is adapted to set into a notch in a cross bar 175 on the legs 11 of the frame. This frame is arranged for the purpose of facilitating the feeding of the articles to be labelled into position for the conveyor chain 148 to carry them through the machine. For this purpose a pair of belts 176 run along the surface of this frame or platform over driving pulleys 177 on the shaft 143 and

idler pulleys 178 on an idle shaft 179 supported at the outer end of the frame 173.

For the purpose of guiding the bottles B or other articles to be labelled down this frame into engagement with the conveyor 148, I have shown a bar 180 pivoted to the frame 173 at a point 181. This bar has a slot 182 concentric with its pivot and a thumb screw 183 passing through the slot 182 into the frame 173 for securing the bar in any adjustable position. Also pivoted at 181 is a guide 184 having a spring 185 connecting it with the bar 180 and normally oscillating the free end of the guide inwardly toward the belts 176. This forms an adjustable guide with a surface for directing the articles downwardly on the conveyor in central position said surface being yielding to prevent crushing the bottles.

On the other side of the belts 176 I have provided another swinging bar 190 pivoted at 191 on the frame 173. This has a guide 194 movably connected with it by means of an adjusting thumb screw 193 passing through a slotted adjusting member 192. This adjusting member is thus capable of being adjusted to any desired position transversely with respect to the bar 190. It is pivotally connected by means of a bracket 195 with the guide 194 and by a link 196 with the pivot stud 191. In order to provide a substantially parallel motion, a parallel link 197 is provided pivoted to the bar 190 and to a corresponding bracket on the back of the guide 194. A spring 198 normally swings the bar 190 back as far as possible. On the gear 142 is a hub 199 having a roller 200. This roller engages a cam surface 201 on the end of the bar 190 and forces out the bar and its guide 194 in opposition to the spring 198 once during each rotation of the shaft 143. The object of this, as shown in the dotted lines in Fig. 25, is to force the bottle B against the yielding guide 184 hard enough to hold the bottle back and prevent its discharge of the conveyor chain 148. There is one projection 149 on the conveyor chain in each space equal to or greater than the circumference of the sprocket wheel 148 so the conveyor chain takes a bottle for each revolution. Therefore, the roller 200 can be spaced in such position on the shaft 143 that the bottle will be held back until just time for one of the projections 149 to come into position to engage its rear end immediately after it is discharged on the platform 156.

The articles are delivered on a platform 211 carried by a frame 210 pivoted on studs 155 carried by a fork 154 integral with the platform 156. In Fig. 21 I have shown another form of gum roll or cylinder 202. This is mounted on the shaft 96 as in the former case but instead of having a series

of continuous grooves around it, it is provided with a plurality of segmental plates 203, each one having alternate grooves 204 and cylindrical surfaces 205. These plates are fixed in position by screws 206 and 70 the spaces on each side of them circumferentially are below the level or inside the circle of the surfaces 205. In this construction a label is taken on each one of these surfaces instead of having the whole 75 circumference for that purpose. This uses less glue than in the other case and is particularly adapted for those machines that are to be used always for labels of the same length. Between this cylinder 20 and 80 the gum roll 88 I have shown contact with both. This ensures feed of gum even after the surfaces or bearings are much worn.

Operation.

85

Although I have specified the operation of several parts in connection with the detailed description thereof, I will describe the operation of the whole machine. It will be understood that the glue pot 80 is filled with 90 liquid glue or other adhesive and that the machine is driven at a high rate of speed, this being possible on account of the fact that the most of the parts are rotary and especially the heavy ones. The rotation of 95 the main shaft 12 carries with it, of course, the two cams 14 and 15 and as stated above their rotation positively reciprocates the yoke 18 carrying with it the upper ends of the levers 20 and 27 and also carrying with 100 it directly the yoke 28. This yoke through its connections oscillates with it the corresponding yoke 29 at the other end of the machine. The action of this oscillating motion is to carry the label frame 33 back and 105 forth positively moving in a horizontal path. The labels L in the label holder between the side frames 37 are pressed forward by the follower 56 actuated by the weight 54. This forward pressure is removed by the action of the clutch but the follower remains in place. The label guard 66 is held up against the front of the labels as shown in full lines in Fig. 18 by the 110 action of the cam 61 until such time as the label holder has moved almost to its limiting position shown in dotted lines in Fig. 18. At this time the action of the stationary cam slot 62 on the lever 67 brings the label guard down away from the label into the 115 dotted line position in that figure where it is out of the way. The top guard 78 is positively held in the position shown in dotted lines in that figure so that the labels cannot be dislodged at the top. Now, when 120 the label holder comes into its dotted line position suddenly, on account of the shape of the cams 14 and 15, the rotating gumming cylinder 100 applies its glue to the rear surface of the first label and instantly brings 125 130

the label down edgewise out of the label holder on account of its rotation. There is only a small lip 104 at the bottom and the top guard 78 does not interpose any resistance. The labels are loose at this time, therefore, the label passes along down with the surface of the gumming cylinder 100 and the next label is not dislodged or disturbed. About this time the label holder 10 starts to move back and the label guard 66 moves upwardly to engage the front label and positively hold it against displacement but the label under discussion passes down. If its lower edge has been turned back by 15 the lip on the bottom of the label holder or if it has failed to come into contact with the glue and therefore does not stick to the gumming cylinder it will be prevented from moving down away from the drum materially by the discs constituting the guide roll 115. Therefore, the label will be moved along circumferentially so that its forward edge will move in between the gumming cylinder 100 and the contact roll 108. This 20 presses the label firmly against the surface of the drum and insures a full coating of glue upon the label put on in spaced stripes. Further travel of the label results in its being combed off the gumming cylinder 100 by the comb 123 and forced to turn upon itself as indicated in Fig. 18 and move forwardly instead of backwardly. Its extreme edge strikes the bottle B near the front end as that is coming along, properly timed with 25 respect to the operations of the label holder, and the pressure roll 118. The surface speed of the latter is substantially the same as that of the pressure roll. The jumping up of the rear end of the bottle at this time 30 is prevented by the anti-jump roll 130 as stated above.

The feeding of the bottles or other receptacles has also been described but they are put in by hand or machine on the feeding belts or tapes 176. Periodically the guide 194 is forced over as shown in Fig. 25 to grip the bottle against the yielding guide 184. This holds the bottle back until the proper projection 149 is in position to engage its rear end and then it is released by the withdrawal of the guide 194 due to the cam 201 and the spring 198. The bottle drops on the conveyor gently just as the projection 149 comes around into position 55 to engage it and the conveyor carries it up on an incline at the same rate as that at which the surfaces of the rolls 118, 108 and the gumming cylinder 100 are travelling. The roll 115 travels at a greater surface 60 speed.

In this way a machine is provided which can be rotated at a high speed, attended by comparatively unskilled laborers, fed with bottles or receptacles either by hand or mechanically, and operated with a high de-

gree of efficiency and a small percentage of stops and breaks, for the purpose of labeling bottles, cans, jars, paste-board receptacles, and cartons, and in fact, anything which is to be labelled in large quantities. 70 As has been stated throughout the specification, it will be understood that the parts are designed for high speed and constant operation and that they are of such a nature as to permit of all desired flexibility of operation without constant attention by a skilled mechanic. 75

Although I have illustrated and described only a single form of the invention, I am aware of the fact that modifications can be 80 made therein by any person skilled in the art without departing from the scope of the invention as expressed in the claims. Therefore, I do not wish to be limited to all the details of construction or the specific 85 combinations of parts herein shown and described, but what I do claim is:—

1. In a label gumming and feeding device, the combination of a gumming member, a label holder adapted to hold the labels with 90 one exposed in position to be engaged by the gumming member, a guard plate arranged to move between the label holder and gumming member to hold the labels back temporarily and means for moving the label holder away from the gumming member to 95 detach the label from the holder and leave it adhering to the gumming member.

2. In a label feeding device, the combination with a gumming member having a movable gum carrying surface, of a label holder movable toward and from the gumming member, and adapted to deposit a label thereon flatwise, and a guard plate movable edgewise to and from a position in front of 105 the labels in the holder to hold them when not in contact with the gumming member.

3. In a label feeding device, the combination with a gumming member having a movable gum carrying surface, of a label holder movable toward and from the gumming member, and supporting a bundle of labels vertically on edge, said holder being movable in a direction transverse to the plane of the exposed end label so as to cause the entire surface across the exposed label to be 115 moved simultaneously against the gumming member.

4. In a label feeding device, the combination of a label holder, means for moving the label holder, said label holder comprising a pair of vertical side walls adjustable toward and from each other, and a horizontal plate at the bottom for receiving the supporting bottoms of the labels having a slight lip extending upwardly from its front upper edge. 120

5. In a label feeding device, the combination of a rotary gumming member, with a label holder adapted to hold the exposed label in vertical position to be engaged by 130

the gumming member, and means for moving the label holder away from the gumming member to detach the label from the holder, and the label holder having a top 5 guard plate for holding back the upper edge of the front label in the holder at the delivery side thereof.

6. In a label feeding device, the combination 10 of a gumming member, with a label holder adapted to hold the exposed label at its front in position to be engaged by a gumming member, a movable top guard plate having a projection adapted to engage the front surface of the forward label above 15 the gumming member, and means for limiting the forward motion of the top guard plate.

7. In a label feeding device, the combination 20 of a rotary gumming member, with a label holder adapted to hold the exposed label in position to be engaged by the gumming member, means for moving the label holder away from the gumming member to detach the label from the holder, and the 25 label holder having a guard plate pivoted from above, means for limiting the forward motion of the guard plate to hold the upper edges of the labels at the delivery side thereof, and a parallel motion operating means 30 for reciprocating the label holder.

8. In a labeling machine, the combination 35 with a gumming member, of two parallel sets of levers, means for oscillating the levers, a pair of horizontal rails pivotally supported by the levers over the gumming member, a label holder depending from and supported by said rails and having means for supporting labels on edge therein in such position that when the rails move in one direction the exposed label at the end of the label holder will be brought into contact with the surface of the gumming member so as to adhere thereto.

9. In a labeling machine, the combination 45 with a gumming member, of two sets of levers, means for oscillating the levers, a pair of rails supported by the levers and movable therewith, a label holder supported by said rails and having means for supporting labels on edge in such position that when the rails move in one direction the exposed label at the end of the label holder will be brought into contact with the surface of the gumming member.

55 10. In a labeling machine, the combination 50 with a gumming member, of a pair of rails, means for moving the rails back and forth, a label holder supported by said rails and having means for supporting labels on edge in such position that when the rails move in one direction the exposed label at the end of the label holder will be brought into contact with the surface of the gumming member.

65 11. In a labeling machine, the combina-

tion with a gumming member, of two sets of levers, means for oscillating the levers, a pair of rails supported by the levers and movable therewith, a label holder supported by said rails and having means for supporting labels on edge in such position that when the rails move in one direction the exposed label at the end of the label holder will be brought into contact with the surface of the gumming member, and means operated by 70 one of said levers for releasing the end label at that time.

12. In a labeling machine, the combination 75 with a gumming member, of a pair of movable rails, a label holder supported by said rails and having means for supporting labels on edge in such position that when the rails move in one direction the exposed label at the end of the label holder will be brought 80 into contact with the surface of the gumming member; a guard for controlling the position of the front of the exposed label, a lever on which said guard is mounted, and means for operating the lever at the end of the stroke of the rail to loosen the end labels. 85

13. In a labeling machine, the combination 90 with a gumming member, of a pair of rails, a label holder supported by said rails and having means for supporting labels on edge in such position that when the rails move in one direction the exposed label at the end of the label holder will be brought 95 into contact with the surface of the gumming member, and means for reciprocating said rails toward the gumming member.

14. In a labeling machine, the combination 100 with a gumming member, of a pair of movable rails, a label holder supported by said rails and having means for supporting labels in such position that when the rails move in one direction the exposed label at the end of the label holder will be brought 105 into contact with the surface of the gumming member, and a counterweighted follower in the label holder to keep the labels in proper position therein.

15. In a labeling machine, the combination 110 with a gumming member, of a pair of movable rails, a label holder supported by said rails and having means for supporting labels on edge in such position that when the rails move in one direction the exposed label at the end of the label holder will be brought 115 into contact with the surface of the gumming member, a follower in the label holder to keep the labels in proper position therein, and means supported by the rails by which said follower is constantly held against the rear label.

16. In a labeling machine, the combination 120 with a gumming member, of a pair of movable rails, a label holder supported by said rails and having means for supporting labels in such position that when the rails move in one direction the exposed label at 125 130

- the end of the label holder will be brought into contact with the surface of the gumming member, a follower in the label holder to keep the labels in proper position therein, 5 a slide on the rails to which said follower is pivoted, and a clutch device for preventing the follower from moving forward relative to the label holder but allowing it to move backward.
- 10 17. In a device of the character described, the combination with a gumming cylinder, of a label holder supported near the gumming cylinder and adapted to move into a position to press an exposed label on the 15 surface thereof, and means for periodically moving the label holder away from the gumming cylinder to detach an exposed label from it, said means comprising a cam rotatable with the gumming cylinder, and a 20 roller connected with the label holder and engaging the cam.
18. In a device of the character described, the combination with a gumming cylinder, of a label holder supported above the cylinder and adapted to move into a position to 25 press an exposed label on the surface thereof, and means for periodically moving the label holder away from the gumming cylinder to detach an exposed label from it, the 30 label holder having a guard for engaging the exposed label movable away therefrom to facilitate its removal from the label holder.
19. In a label feeding device, the combination 35 of a gumming cylinder, a label holder adapted to hold the exposed label in position to be engaged thereby, means for moving the label holder away from the gumming cylinder to detach the label from the holder, a guard for the front of the label 40 holder against which the exposed label normally rests, and means for swinging said guard from between the exposed label and the cylinder to a point beyond them when the label holder approaches the cylinder.
20. In a label feeding device, the combination 45 with a gumming cylinder, of a label holder reciprocable horizontally toward and from the cylinder, said label holder having a horizontal bottom on which the lower 50 edges of the labels rest in vertical position, said cylinder being located just in front of the front exposed label, and movable means for holding the front label near the center.
21. In a labeling machine, a label holder 55 comprising a pair of simultaneously and oppositely adjustable sides with horizontal bottom for supporting the labels on edge vertically between said sides, a follower 60 for pressing on the rear labels to hold and feed them uniformly forward, a weight acting to force the follower forward and a guard plate for engaging the upper edge of the front label to hold back those behind it.
22. In a label feeding device, the combina- 65
- tion of a frame, means for moving said frame horizontally, a pair of side frames carried by said frame to receive the labels between them, a bottom on which said side frames are supported for supporting the 70 bottom edges of the labels in a substantially vertical position, a label guard movably mounted, and means for moving said guard into contact with the front label to hold the labels back in the label holder and for moving it out of contact with the labels to permit of their being removed from the holder. 75
23. In a label feeding device, the combination with a horizontally reciprocable label holder having a horizontal bottom on which the lower edges of the labels can rest substantially in vertical position, said bottom having a small upwardly extending front lip for engaging the front surface of the front label, means for holding the top of the front label but permitting it to be moved downwardly, a guard for the front label, and means for moving said guard into contact with substantially the center of said label and for moving it down past the end 80 of said bottom.
24. In a label feeding device, the combination with a horizontally reciprocable label holder having a horizontal bottom on which the lower edges of the labels are adapted to rest in vertical position, said bottom having a small upwardly extending front lip for engaging the front surface of the bottom of the front label, means for holding the top of the front label but permitting it to be moved downwardly, a guard for 85 engaging the front label, and means for moving said guard into contact with substantially the center of said front label and for moving it down past the end 90 of said bottom.
25. In a label feeding device, the combination with a horizontally reciprocable label holder having a horizontal bottom on which the lower edges of the labels are adapted to rest in vertical position, means for holding the top of the front label but permitting it to be moved downwardly, a guard for 95 engaging the front label, and means for moving said guard into contact with said front label and for moving it down past the end of said bottom, said guard being pivotally supported on said label holder. 100
26. In a label feeding device, the combination with a horizontally reciprocable label holder having a horizontal bottom on which the lower edges of the labels are adapted to rest in vertical position, a guard for 105 engaging the front label, and means for moving said guard into contact with said front label and for moving it past said bottom, said guard being supported on said label holder. 110
27. In a label feeding device, the combi- 115

5 nation of a reciprocable frame, a label holder mounted thereon to reciprocate therewith, a guard for the labels in the holder adapted to engage the front label and hold it in position, said guard being pivotally mounted on said frame, and stationary means for raising and lowering the guard as the frame reciprocates.

10 28. In a label feeding device, the combination of a reciprocable frame, a label holder mounted thereon to reciprocate therewith, a guard for the label holder adapted to engage the front label and hold it in position, arms pivoted on said frame, a stationary cam for swinging said arms up and down as the frame reciprocates, said guard being pivoted on said arms, and stationary means for swinging said guard on its pivot in the general direction in which the frame 15 moves as the arms are raised and lowered.

20 29. In a label feeding device, in combination with a reciprocable frame, of a label holder on said frame, arms pivotally supported by said frame, a cam, a roll on one 25 of said arms engaging the cam, said cam having a shape adapted to raise said arms by means of the roll as the frame moves back from delivering position and to hold the arms in raised position thereafter during 30 its backward motion, a lever pivoted on said arms and having an upwardly extending portion provided with a label guard extending across the front of the label holder when the arms are raised, and a 35 second cam having a shape for swinging said lever as the label holder is reciprocated and forcing the guard back against the labels at all times except when the label holder moves forward to delivering position.

40 30. In a label feeding device, in combination with a reciprocable frame, of a label holder on said frame, arms pivotally supported by said frame and projecting forwardly under the frame, a stationary cam, a roll on one of said arms engaging the cam, said cam having a shape adapted to cause said arms to rise by means of the roll as the frame moves back from delivering position and to hold the arms in raised position thereafter during its backward motion and to lower the arms when the label holder moves to its extreme forward position for delivery, a lever pivoted on said arms and having an upwardly extending portion provided with a label guard extending across the front of the label holder when the arms are raised, and a stationary cam constituting means for swinging said lever as the label holder is reciprocated and forcing the guard back against the labels and swinging the label guard forward to loosen the labels just before the arms descend.

45 31. In a label feeding device, the combination of a reciprocable label holder, a follower beam slidable back and forth with the label holder, a follower fixedly mounted on the rear end of the follower beam for engaging the labels in the label holder, means constantly tending to move the follower beam and follower forward, and a clutch acting to prevent forward movement of the follower beam.

50 32. In a label feeding device, the combination of a reciprocable frame, a label holder movable therewith, a horizontal follower beam slidable back and forth with the label holder, a follower fixedly mounted on the rear end of the follower beam for engaging the labels in the label holder, means for constantly tending to move the follower beam and follower forward but capable of permitting them to be moved back by hand at all times, and a clutch engaging the follower beam and acting when in operative condition to prevent further forward movement of the follower beam.

55 33. In a label feeding device, the combination of a reciprocable frame, a label holder movable therewith, a horizontal follower beam slidable back and forth with the label holder, a follower fixedly mounted on the rear end of the follower beam for engaging the labels in the label holder, means for constantly tending to move the follower beam and follower forward but capable of permitting them to be moved back by hand at all times, a pivoted clutch member engaging the follower beam to prevent forward movement thereof, a lever on which said clutch member is mounted extending in such direction as to force the clutch against the follower beam at a point at the rear of the pivot on which the lever is mounted.

60 34. In a label feeding device, the combination of a reciprocable label holder, a follower beam slidable back and forth with the label holder, a follower on the end of the follower beam for engaging the labels in the label holder, means for constantly tending to move the follower beam and follower forward, a pivoted clutch member engaging the follower beam, a lever on which said clutch member is mounted extending from the clutch in such a direction as to force the clutch against the edge of the follower beam at a point at the rear of the pivot on which the lever is mounted, yielding means for connecting the clutch lever with the frame on the side of its pivot on which the clutch is located, whereby the clutch will move forward yielding into operative position as the frame moves forward and positively lock the follower against moving forward more rapidly than the frame.

65 35. In a label feeding device, the combination of a reciprocable label holder, a 130

follower beam slidable back and forth with the label holder, a follower fixedly mounted on the rear end of the follower beam, means for moving the follower beam and follower forward, a clutch engaging the follower beam and acting when in operative condition to prevent further movement of the follower beam, a pivoted lever having an upwardly extending arm inclined rearwardly on which said clutch is located, said lever extending below the pivot, and adjustable ends thereon for engaging a movable part of the apparatus to disengage the clutch automatically when the label holder moves back beyond a certain point from position for delivery.

36. In a label feeding device, the combination with a reciprocable label holder, of a follower for the labels and the holder, a follower beam movable with the holder, a clutch for engaging the bottom of said beam to hold it against motion in a forward direction, a plate bearing on said beam on the edge opposite the clutch, and means mounted on a stationary part of the machine for adjusting said plate in a direction transverse to the direction of motion of the follower beam.

37. In a label feeding device, the combination with a reciprocable label holder adapted to have labels supported therein in a vertical position, and comprising a pair of pivoted side walls, of cams projecting from said side walls, and stationary means adapted to be engaged by said cams when the label holder moves forward to delivery position for swinging back said sides to permit the front label to project beyond their front edges at the instant of delivery.

38. In a label feeding device, the combination with a reciprocable frame, a label holder mounted to move therewith having labels supported therein in a vertical position, a pair of sides pivoted on said frame and constituting the side walls of the label holder, cams projecting from said sides, stationary means in position to be engaged by said cams when the frame moves forward to delivery position for retracting the lower front edges of said sides to permit the front label to project beyond them at the instant of delivery, and a gumming cylinder located in position to engage the front label when the sides are drawn back, said cylinder being rotatable in a direction to which the label at that time is tangent.

39. In a label feeding device, the combination with a reciprocable frame, a label holder mounted to move therewith for supporting labels therein in a vertical position, a pair of sides pivoted on said frame and constituting the side walls of the label holder, cams projecting from said sides, means adapted to be engaged by said cams

when the frame moves forward to delivery position for swinging said sides back and thus drawing back the lower front edges of said sides to permit the front label to project beyond them at the instant of delivery, and means whereby said sides can be raised about their pivots and held in raised position temporarily.

40. In a label feeding device, the combination of a frame, a pair of side members pivoted on a transverse axis on said frame and constituting with the frame a label holder, a hook pivoted on one of said side members, and a cross bar above, which said hook is adapted to engage for the purpose of holding the side up in inactive position.

41. In a label feeding device, the combination with a frame, of a driving shaft, a pair of yokes mounted to swing on parallel axes, means for connecting said yokes to cause them to swing together with a parallel motion, and means for swinging said yokes comprising a yoke, cams on said shaft for operating the last named yoke, and pivotal connections between the last named yoke and one of said pair of yokes for swinging them.

42. In a label feeding device, the combination with a frame, of a driving shaft carried thereby, a pair of yokes mounted to swing on parallel axes at the opposite ends of the frame, means for connecting said yokes to cause them to swing together with a parallel motion, and means for swinging said yokes comprising a horizontal yoke having a passage for said shaft, cams on said shaft for operating the last named yoke to move back and forth horizontally, and pivotal connections between the last named yoke and one of said pair of yokes for swinging them.

43. In a label feeding device, the combination with a frame, of a driving shaft carried thereby, a pair of yokes mounted to swing on horizontal axes at the opposite ends of the frame, means for connecting said yokes to cause them to swing together with a parallel motion, a horizontal yoke having a passage for said shaft, cams on said shaft for operating the horizontal yoke to move it back and forth horizontally, and pivotal connections between the horizontal yoke and one of said pair of yokes for swinging them, said pivotal connection comprising a pin, and means whereby said pin can be withdrawn from the first named yoke without detaching it from the horizontal yoke to permit the driving shaft to be operated without swinging said pair of yokes.

44. In a label feeding device, the combination with a frame, of a driving shaft carried thereby, a pair of yokes mounted to swing on horizontal axes, means for connecting said yokes to cause them to swing together with a parallel motion, a label holder

- connected with the first named yokes to be swung with them in a general horizontal direction, a horizontal yoke having a passage for said shaft, cams on said shaft for 5 operating the horizontal yoke to move back and forth horizontally, a pin constituting a pivotal connection between the horizontal yoke and one of the first named yokes, means whereby said pin can be withdrawn 10 from the first named yoke without detaching it from the horizontal yoke to permit the driving shaft to be operated without swinging said pair of yokes, and a gumming device operated by said driving shaft.
- 15 45. In a label feeding device, the combination with a frame, of a driving shaft carried thereby, a pair of yokes mounted to swing on parallel axes, means for connecting said yokes to cause them to swing together with a parallel motion, a label holder carried by said frame movable forward therewith, a horizontal yoke, cams on said shaft for operating the horizontal yoke to move back and forth, said yokes extending 20 upwardly from their points of pivotal support and connected at the top by horizontal bars, said frame being supported by said bars at one end, and a gumming cylinder operated by said shaft and located in position 25 to be engaged by the front label in the holder when it moves forward.
46. In a label feeding device, the combination of a rotary gumming member, with a label holder adapted to hold the exposed 30 label in position to be engaged by the gumming member, means for moving the label holder away from the gumming member to detach the label from the holder, said gumming member having a series of circumferential grooves, a plate having projections 35 adapted to enter said grooves, and a parallel motion operating means for reciprocating the label holder.
47. In a label feeding device, the combination 40 of a gum cylinder having circumferential grooves, a contact roll located in position to engage a label carried by the gum cylinder, a comb projecting into the grooves of the gum cylinder to positively remove the labels therefrom, and a soft surfaced roll 45 in position to receive the label and press it on an article to be labelled.
48. In a label feeding device, the combination 50 of a gum cylinder having circumferential grooves, a contact roll having circumferential grooves alternating with the grooves of the gum cylinder located in position to engage a label carried by the gum cylinder, a comb fixed in position and projecting into the grooves of the gum cylinder to positively remove the labels therefrom, and a soft surfaced roll driven from the gum cylinder in position to receive the label 55 therefrom and press it on an article to be labelled.

49. In a label feeding device, the combination of a gum cylinder having grooves, a contact roll having grooves alternating with the grooves of the gum cylinder, the contact roll being in position to engage a 70 label carried by the gum cylinder, a conveyor located in position to convey the articles to be labelled adjacent to the roll, and a soft surfaced roll in position to press the labels on the surface of the articles as they 75 pass it on the conveyor.

50. In a label feeding device, the combination of a gum cylinder having circumferential grooves, a contact roll having circumferential grooves alternating with the 80 grooves of the gum cylinder, the contact roll being in position to engage a label carried by the gum cylinder, a comb fixed in position and projecting into the grooves of the gum cylinder to positively remove the 85 labels therefrom, a conveyor located in position to convey the articles to be labelled adjacent to the gum cylinder, and a soft surfaced roll in position to press the labels on the surface of the articles as they 90 pass it on the conveyor.

51. In a label feeding device, the combination with a reciprocable label holder, a gumming cylinder in position to be engaged by the front label and rotatable to carry the 95 front label out of the holder and for carrying it around with it thereafter, and a guide roll located in position to engage the front edge of the label, whereby the leading edge of the label will be forced back toward the 100 gumming cylinder.

52. In a label feeding device, the combination with a reciprocable label holder adapted to support the labels in vertical position, a gumming cylinder in position to be engaged by the front label when the holder moves forward to its extreme position and rotatable to carry the front label out of the holder without changing its direction at the instant of discharge and for carrying 110 it around with it thereafter, a guide roll located in position to engage the front edge of the label, and means for rotating said guide roll at a surface speed greater than that of the cylinder, whereby the leading edge of the label will be forced back toward the 115 gumming cylinder.

53. In a label feeding device, the combination with a reciprocatable label holder, a rotary gumming cylinder in position to be 120 engaged by the front label when the holder moves forward to its extreme position and carries the front label out of the holder without changing its direction at the instant of discharge and for carrying it around with it thereafter, a guide roll consisting of a series of spaced circular discs located in position to engage the front edge of the label, and means for rotating said guide roll at a 125 surface speed greater than that of the cylinder.

inder, whereby the leading edge of the label will be forced back toward the cylinder.

54. In a label feeding device, the combination with a reciprocable label holder adapted to support the labels in vertical position, a gumming cylinder in position to be engaged by the front label when the holder moves forward to its extreme position and rotatable to carry the front label out of the holder in a tangential direction at the instant of discharge and for carrying it around with it thereafter, a guide roll located in position to engage the front edge of the label, means for rotating said guide roll at a surface speed greater than that of the cylinder, whereby the leading edge of the label will be forced back toward the cylinder, and a contact roll located beyond the guide roll and adapted to force the labels into contact with the surface of the gumming cylinder.

55. In a label feeding device, the combination with a reciprocable label holder, a gumming cylinder in position to be engaged by the front label for carrying the label around with it, a guide roll comprising a series of circular discs located in position to engage the front edge of the label, means for rotating said guide roll at a surface speed greater than that of the cylinder, and a contact roll comprising a series of circular discs projecting between the discs of the guide roll located beyond the guide roll and adapted to force the labels into contact with the surface of the gumming cylinder.

56. In a labeling device, the combination with a gumming cylinder having a circumferentially grooved surface, of means for introducing a label on the surface of said gumming cylinder, a comb projecting into the grooves of the cylinder for stripping the labels from the cylinder and forcing them to move away from it in a path, pins projecting toward the opposite ends of the cylinder, one at each end arranged to support the comb and one to limit its backward motion, and a third pin on one end for holding the comb down on the first pin.

57. In a labeling device, the combination with a gumming cylinder having a circumferentially grooved surface, of means for introducing a label on the surface of said gumming cylinder, means for rolling the label on the cylinder throughout its length, and a comb projecting into the grooves of the cylinder and having a substantially cylindrical concave surface for stripping the labels from the cylinder and forcing them to move away from it in a curved path, said comb having projections, constituting a reverse continuation of the curved surface of the cylinder for turning the labels around and bringing them into a position at their ends in which they move in a direction substantially opposite to the direction of motion

of the adjacent surface of the gumming cylinder.

58. In a labeling device, the combination with a gumming cylinder having a circumferentially grooved surface, of a comb projecting into the grooves of the cylinder and having a concave surface for stripping the labels from the cylinder and forcing them to move away from it in a curved path, said comb having projections, the surfaces of which constitute a continuation of said curved surface but extending in a direction at one end opposite that of the entering edge of the comb for turning the labels around and bringing them into a position in which they move in a direction substantially opposite to the direction of motion of the adjacent surface of the gumming cylinder, means for bringing the article to be labelled into contact with a label at that point, and a pressure roll for pressing the label against the article.

59. In a labeling device, the combination with a gumming cylinder having a circumferentially grooved surface, of means for introducing a label on the surface of said gumming cylinder, means for rolling the label on the cylinder throughout its length, a comb projecting into the grooves of the cylinder and having a concave surface for stripping the labels from the cylinder and forcing them to move away from it in a curved path, said comb having projections the surfaces of which constitute a continuation of said curved surface for turning the labels around and bringing them into a position at their ends in which they move in a direction substantially opposite to the direction of motion of the adjacent surface of the gumming cylinder, means for bringing the article to be labelled into contact with a label at that point, a pressure roll for pressing the label against the article, and a spring pressed roll for engaging the rear end of the article to be labelled and preventing its jumping up when the pressure roll engages it.

60. In a labeling device, the combination with a gumming cylinder, of means for introducing a label on the surface of said gumming cylinder, a comb for stripping the labels from the cylinder and forcing them to move away from it, means for bringing the article to be labelled into contact with a label, a pressure roll for pressing the label against the article and a spring pressed roll for engaging the rear end of the article to be labelled and preventing its jumping up when the pressure roll engages it.

61. In a labeling device, the combination with a gumming cylinder having a circumferentially grooved surface, of a comb projecting into the grooves of the cylinder and having a surface for stripping the labels

from the cylinder and forcing them to move away from it, said comb having projections the surfaces of which constitute a continuation of said surface for turning the labels 5 around and bringing them into a position in which they move in a direction substantially opposite to the direction of motion of the adjacent surface of the gumming cylinder, means for bringing the article to be labelled into contact with a label at that point, a pressure roll for pressing the label against the article, a spring pressed jump roll for engaging the rear end of the article 10 to be labelled and preventing its jumping up when the pressure roll engages it, a pivoted frame having arms projecting therefrom on which the jump roll is mounted, an arm projecting therefrom in the opposite direction, and a stationary stop for the last 15 named arm.

62. In a labeling device, the combination with a gumming cylinder having a circumferentially grooved surface, of means for introducing a label on the surface of said gumming cylinder, means for rolling the label on to the cylinder throughout its 20 length, and a comb projecting into the groove of the cylinder and having a concave surface for stripping the labels from the cylinder and forcing them to move away 25 from it in a curved path, said comb having projections, the surface of which constitute a continuation of said curved surface for turning the labels around and bringing them 30 into a position in which they move in a direction substantially opposite to the direction of motion of the adjacent surface of the gumming cylinder, a pressure roll for pressing the label against the article, and an endless conveyor 35 provided with a platform through which the conveyor projects and parallel with it for supporting the articles to be labelled.

63. In a labeling device, the combination with a gumming cylinder, of a comb having a surface for stripping the labels from the cylinder and forcing them to move away 45 from it for turning the labels around and bringing them into a position in which they move in a direction substantially opposite to the direction of motion of the adjacent surface of the gumming cylinder, a pressure roll for pressing the label against the article, and an endless conveyor provided with a platform through which the conveyor projects and parallel with it for supporting the articles to be labelled.

64. In a labeling machine, the combination with a gumming cylinder, of a label holder open at the end and means for swinging said label holder forward and bringing said open end into contact with the cylinder at an increased speed and suddenly separating them.

65. In a labeling machine, the combination with a gumming cylinder, of a label holder open at the end and means for swinging said label holder forward and suddenly bringing said open ends into contact with the cylinder and suddenly separating them, and means for suddenly relieving the labels in the holder from pressure as the holder reaches its extreme forward position against the cylinder.

66. In a labeling machine, the combination with a gumming cylinder, of a label holder open at the end and means for moving said label holder forward and bringing said open end into contact with the cylinder and then separating them, and means for suddenly relieving the labels in the holder from pressure as the holder reaches its extreme forward position against the cylinder.

In testimony whereof I have hereunto affixed my signature.

HORATIO GATES.
